Primary Examiner — Garth Rademaker*Assistant Examiner* — LLorelys Martinez-Rivera(74) *Attorney, Agent, or Firm* — Garrett V. Davis; Mark S. Bicks; Alfred N. Goodman(57) **CLAIM**

The ornamental design for a nightlight, as shown and described.

DESCRIPTION

FIG. 1 is a perspective view of a nightlight, shown mounted in a faceplate;

FIG. 2 is a top view of the nightlight of FIG. 1;

FIG. 3 is right side view of the nightlight of FIG. 1;

FIG. 4 is a left side view of the nightlight of FIG. 1;

FIG. 5 is a front view of the nightlight of FIG. 1; and,

FIG. 6 is a rear view of the nightlight of FIG. 1.

The broken lines depict environmental subject matter only and form no part of the claimed design.
